UNITED STATES PATENT OFFICE.

OLIVER SELLE, OF ST. LOUIS, MISSOURI.

BELT-BUCKLE.

1,323,917.

Specification of Letters Patent.

Patented Dec. 2, 1919.

Application filed May 19, 1919. Serial No. 298,229.

To all whom it may concern:

Be it known that I, OLIVER SELLE, a citizen of the United States, and a resident of St. Louis, in the State of Missouri, have invented a new and Improved Belt-Buckle, of which the following is a full, clear, and exact description.

The present invention relates to new and useful improvements in belts and pertains more particularly to a buckle therefor.

The primary object of the invention is to provide a device of this character in which the tang of the buckle may be readily engaged with or disengaged from the free end of the belt.

A further object of the invention is to provide a device of this character in which the greater the strain imparted to the tang of the buckle, the tighter said tang engages the free end of the belt.

With the above and other objects in view, reference is to be had to the accompanying drawings in which—

Figure 1 is a top plan view;

Fig. 2 is a longitudinal sectional view on the line 2—2 of Fig. 1;

Fig. 3 is a transverse sectional view on the line 3—3 of Fig. 1.

Referring more particularly to the drawings, the buckle comprises a body portion 5 formed of any suitable sheet metal, and on opposite sides of said body portion 5 and arranged at right angles thereto are flanges 6. Each of these flanges 6 is provided with an elongated slot 7, which is angularly disposed with respect to said body portion, and slidably mounted in said angularly disposed slots 7, is a transversely-extending rod 8, the ends of said rod being upset to form heads 9, by means of which it is retained in place.

Pivottally mounted on the transversely extending rod 8, is a tang 10, which consists of a shank portion 11 and a hook end 12. The tang 10 is pivotally mounted about the transversely extending rod 8, by means of a sleeve 13, with which the tang 10 is cast integral, and said sleeve is formed intermediate of its ends with an enlarged portion 14.

Pivottally mounted between the flanges 6 near one end of the body portion of the

buckle, is a link 15, and said link is provided with right-angularly disposed extensions 16, which form the pivotal points thereof.

In operation one end of the belt is looped about the link 15, and is secured by means of a suitable end fastener or the like 17. The other end 18 of the belt is passed around the body of the wearer and is inserted into the buckle between the sleeve 13 and the body portion 5 of said buckle. The free end of the belt is now pulled through the buckle until the hook end 12 of the tang 10 engages in one of the openings 19 of the belt.

If, now, the free end of the belt be released, it will be seen that any strain exerted on the belt behind the buckle would cause the tang to more firmly maintain itself within the opening 19 with which it is engaged, and by reason of contact of the sleeve 13 with the belt 18, the hook end of the tang is further maintained in engagement with the opening 19. Owing to the fact that the transversely extending rod 8 on which the tang is mounted, is slidable in the slots 7, and said slots are angularly disposed as shown in Fig. 2, a pull on the belt behind the buckle causes said rod to ride up the incline of the slot 7, forming an additional grip between the sleeve 13 and the body portion 5 of the buckle.

When it is desired to remove the belt, the free end thereof is grasped and pulled, which action swings the tang about its pivotal point and disengages its hook end from the opening in the belt, in which position the belt is free to be removed from the buckle 5.

Having thus described the invention, what is claimed as new is:

1. A belt buckle comprising a body portion provided with opposite-disposed and angularly slotted flanges, a transversely extending rod movable longitudinally of the angular slots in the flanges, and a belt-engaging tang pivotally mounted on said rod and movable therewith with respect to the body portion of the buckle.

2. A device of the character described comprising a flanged body portion having angularly disposed slots, a transversely extending rod slidably mounted in said an-

gularly disposed slots, a sleeve rotatably mounted on said rod, and a belt engaging tang rigidly carried by said sleeve, and adapted for engagement with a belt upon movement of the sleeve on the transverse rod.

3. A device of the character described comprising a body provided with oppositely

disposed angularly slotted flanges, a transversely extending rod mounted in said angular slots, a belt engaging tang carried by said rod, and means for frictionally engaging said belt for simultaneously engaging said tang with said belt.

OLIVER SELLE.
